United States Patent Office

Des. 232,764
Patented Sept. 10, 1974

232,764

TRASH COMPACTOR DEVICE

Arthur B. Turley, 1216 S. Kentucky,
Sedalia, Mo. 65301

Filed Nov. 3, 1972, Ser. No. 303,537

Term of patent 14 years

Int. Cl. D15—99
U.S. Cl. D55—1 B

Fig. 2.

Fig. 1.

FIG. 4.

FIG. 3.

FIG. 1 is a perspective view of a trash compactor device showing one end and one side thereof;

FIG. 2 is an end view of the opposite end of the trash compactor device from the one shown in FIG. 1;

FIG. 3 is a side elevational view of the opposite side of the trash compactor device from the one shown in FIG. 1; and

FIG. 4 is a top plan view of the trash compactor device. I claim:

The ornamental design for a trash compactor device, as shown.
